UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 12, 1923. Serial No. 680,154.

This invention relates to typewriting machines, and more particularly to machines especially adapted for writing checks or similar instruments and for making a copy on a 5 continuous record-sheet of a part of the matter typed on each check of a series.

In writing checks it is customary to insert each check in the typewriter and type two lines upon it. The first line consists of the 10 name of the payee and the numerals indicating the amount for which the check is drawn, and the second line consists of a statement of the amount for which the check is drawn, spelled out in full. It is desirable to keep 15 a condensed record of the checks by copying on a record-sheet the first typewritten line only, of each check. With this end in view, there is provided, in addition to the usual ribbon mechanism for writing on the 20 faces of the checks, an auxiliary ribbon behind the checks but in front of the record-sheet, and mechanism to move the ribbon to and from effective position.

A machine having auxiliary ribbon mechanism of this type is disclosed in the application of Alfred G. F. Kurowski, Serial No. 589,064, filed September 19, 1922, now Patent No. 1,564,861, dated December 8, 1925. The improvements of the present invention 30 are shown as applied to a machine of the kind disclosed in said application. In the Kurowski machine the auxiliary ribbon was carried by ribbon-spools mounted in a ribbon-frame pivoted on the platen-frame. 35 The ribbon-frame was arranged to be lowered to locate the ribbon in operative position as an incident of making the feed-rolls effective following insertion of a check to writing position, and was arranged to be 40 automatically withdrawn from operative position by the actuation of the line-spacing lever at the conclusion of writing the first line on the check. During the insertion of a 45 check in the machine the ribbon was in its ineffective position at some little distance from the platen and so was apt to catch upon the edge of the check inserted first into the machine.

One object of the present invention is to 50 provide efficient means for holding the ribbon down to the platen in both its effective and ineffective positions, so that the checks may be inserted from either the front or the rear of the platen to writing position without danger of fouling the ribbon.

Another object of the invention is to provide means for clamping the record-sheet fast against the platen to prevent accidental shifting of the record-sheet while the main feed-rolls are cast off. 60

With these objects in view, provision may be made of a front rod or bar having ribbon-guide brackets rotatably mounted upon it. These brackets are equipped with guides which may be utilized both to guide the 65 margins of the record-sheet, and also to overlie the auxiliary ribbon to guide it close to the platen at all times. Auxiliary rolls carried by the guides bear upon the margins of the record-sheet to clamp them against 70 the platen. In order that the clamping pressure may be sufficient to hold the record-sheet stationary when the main feed-rolls are cast off, each of the brackets is urged with considerable force in a direction to 75 press its auxiliary roll against the platen by a coil spring connected at one end to the rod and at the other end to the bracket. Rotation of the brackets about the rod is limited by engagement of the rolls with the 80 platen, and the guides themselves are arranged to be spaced just far enough from the platen when the rolls are thus engaged to afford an easy clearance for the ribbon in 85 its movements between effective and ineffective positions.

The ribbon-spools of the auxiliary ribbon-frame lie between the rod and the ends of the platen-frame and therefore prevent the direct connection of the rod to the platen-frame. In accordance with one feature of the invention, provision is made of U-shaped rod-supporting arms pivoted at their outer ends in bearings on the platen-frame and arranged to pass around the ribbon-spools 90 and form supports for the ends of the rod. The rod is supported in this manner in line with the bearings of the rod-supporting arms. Provision is made of means for yieldingly detaining the arms in a position to 95 hold the auxiliary rolls against the platen. 100

The rod-supporting arms may also be used as handles to rotate the rod to swing the ribbon-guides and auxiliary feed-rolls to an ineffective position when it is desired to 105 release the record-sheet or the auxiliary ribbon. To this end, fixed abutments are provided on the rod, one adjacent each of the guide-brackets, to engage the brackets and limit unwinding of the coil springs when the 110

rod is rotated, so that the brackets will be caused to turn with the rod.

To enable the brackets to co-operate in this manner with the fixed stops, they are secured 5 against endwise movement on the rod. Provision is made, however, of means for securing the ribbon-guides in various adjusted positions along the ribbon-guide brackets to provide room between them for the insertion 10 of checks of various widths, and yet to cause them to engage the ribbon as near to the side edges of the checks as practicable.

In accordance with one feature of the invention, provision is made of a front aligning plate for the checks, which is also mounted on the rod that supports the ribbon-guide brackets. The aligning plate has a side-edge gage and leading-edge gaging means for locating the checks. The leading-edge 20 gaging means is of novel construction, consisting of rounded portions at the upper extremity of the aligning plate against which the checks may be placed for gaging, but so constructed that they do not obstruct the 25 feeding forward of the checks. The front aligning plate is adjustable along the supporting rod. It is also rotatable with relation to the rod, so that it may be swung up out of the way independently of rotation of 30 the rod to leave the record-sheet accessible for erasures.

Other features and advantages will hereinafter appear.

In the accompanying drawings,

35 Figure 1 is a front elevation showing a part of the machine with the present improvements applied thereto.

Figure 2 is a fragmentary perspective showing the details of construction of the 40 ribbon-guide-supporting means.

Figure 3 is a fragmentary plan view showing the means for supporting the ribbon-guides and clamping rolls.

45 Figure 4 is a longitudinal vertical section on the line 4—4 of Figure 1, showing the auxiliary ribbon in effective position.

Figure 5 is a longitudinal vertical section on the line 5—5 of Figure 1, showing the auxiliary ribbon in its ineffective position.

50 The typewriting machine to which the present improvements are applied is provided with the usual main ribbon 10, which is fed back and forth between spools (not shown) and is threaded through a ribbon-vibrator 11, between a type-guide 12 and the platen 13, in position to be struck by the types 14 for making impressions on the paper in the machine. The machine is equipped with a wire paper-guide 15 to 55 guide the front-inserted checks A clear of the main ribbon 10, and with forwardly-flaring wing-scales 16 to facilitate the front insertion of the checks between the platen 13 and the paper-apron 17. The platen 13 is 60 rotatably mounted by means of a platen-

axle 18, journaled in a platen-frame 19 in the usual manner. Paper-feed-rolls 20 co-operate with the platen 13 for feeding the checks A and the record-sheet B, and may be cast off by means shown in the patent to 70 Wagner, No. 794,437, dated July 11, 1905, of the kind usually provided in Underwood typewriters.

An auxiliary ribbon 21, arranged to pass 75 between the main ribbon 10 and the platen 13 to print upon the record-sheet B, is mounted upon and controlled by mechanism like that disclosed in the application of Kurowski referred to above. An auxiliary ribbon-frame, comprising end plates 22 and 80 a rock-shaft 23 journaled in the platen-frame 19, supports ribbon-spools 24 just beyond the ends of the platen 13 for rotation about transverse horizontal axes. The auxiliary ribbon 21 passes from one of the 85 spools 24 through a guide 25 at one end of the platen, thence across the front of the platen through a similar guide 25 at the opposite end thereof and onto the other spool 24. At the line-spacing of the platen 13 to 90 advance the check A and the record-sheet B following the typing of the first line on a check, mechanism disclosed in the above-mentioned Kurowski application is operated to lift the auxiliary ribbon-frame to 95 move the auxiliary ribbon 21 to an ineffective position, and the ribbon-feeding mechanism is actuated at the same operation to feed the auxiliary ribbon 21. The second line on the check A is then written, after 100 which the main feed-rolls 20 are cast off to permit the removal of the finished check and the insertion of a new one. When the new check has been inserted, the main feed-rolls 20 are again made effective, and, by the same 105 operation, the auxiliary ribbon 21 is automatically lowered to effective position.

In accordance with the present invention, provision is made of ribbon-guides 26 for holding the auxiliary ribbon 21 down close to the platen 13 when the auxiliary-ribbon-frame is swung to render said ribbon ineffective.

Each ribbon-guide 26 has bearings 27 supporting a paper-feeding and paper-holding roll 28, and is mounted on a bracket 29 rotatable upon a rod or rock-shaft 30 located above the platen 13. This rod 30 is itself mounted for rotation in a manner to be described, to swing the guides 26 and clamping rolls 28 away from the platen when desired, but is normally yieldingly detained in position to render the guides 26 and rolls 28 effective. Each bracket 29 comprises a U-shaped bearing member 31, including legs 32 rotatably received on the rod 30, and a guide-supporting member 33 having a portion 34 by which it is attached to the bearing member 31, a laterally-extending portion 35 to which the guides 26 are attached by screws 130

36, a downwardly-extending portion 37, and a shelf portion 38 for guiding the record-sheet away from the platen. The bearing member 31 of the bracket 29 is mounted between 5 collars 39 and 40 made fast on the rod 30 by screws 41 and 42, respectively. A coil-spring 43, surrounding the rod, is attached at one end to a collar 44 fast on the rod 30 and is connected at the other end to an arm 45 of the bearing member 31 to urge it in a direction to press the guide 26 toward the platen, which cooperates with the guide in controlling the ribbon 21; the guide-pieces serving as fenders to ward off the auxiliary 10 ribbon from the path or course by the statement-sheets as they are inserted at the front of the platen. The head of the screw 41 is made large to serve as an abutment to engage the arm 45 and limit rotation of the bracket 29 relatively to the rod 30. The arrangement is such that the roll 28 is normally pressed against the platen 13 with considerable force by the spring 43, the engagement of the roll with the platen acting 15 to swing the arm 45 out of engagement with the head of the screw 41 against the force of the spring 43. The guide 26 and the roll 28 carried by it are so arranged that the roll spaces the guide far enough from the platen 13 to permit travel of the auxiliary ribbon 21 between effective and ineffective positions.

The auxiliary ribbon-spools 24 prevent the direct connection of the rod 30 to the ends 20 of the platen-frame 19. Provision is therefore made of yokes 47 for supporting the rod 30, which yokes have bearing members 48 rotatably mounted in brackets 49 on the ends 46 of the platen-frame. The yokes 47 extend around the auxiliary ribbon-spools 24 and support the rod 30 in alignment with the bearing members 48 of the yokes. Rotation of the yokes 47 therefore rotates the rod 30 about its own axis. When it is desired to withdraw the ribbon-guides 26, and the rolls 28 carried by them, from the platen, the yokes 47 may be used as handles to rotate the rod 30. It is at this stage, when the clamping rolls 28 are to be swung 25 out of engagement with the platen, that the screw-heads 41 engage the arms 45 of the brackets 29 to limit the unwinding of the springs 43 and to cause the guides 26 to be swung with the rod 30. The bearings 48 of the yokes 47 have key-ways adapted to receive keys 50 pressed by bow springs 51 to 30 yieldingly detain the rod 30 in position to maintain the ribbon-guides 26 and their rolls 28 effective.

For positioning checks inserted in the machine, there is provided a front aligning plate 52, which may also be mounted on the rod 30. The aligning plate is mounted on U-shaped bearing members 53, rotatable on the rod 30 and having keys 54 pressed by

bow springs 55 into a key-way 56 in the rod 30 to yieldingly prevent rotation of the aligning plate relatively to the rod. Finger-pieces 57 are provided, however, for swinging the aligning plate 52 relatively to the rod 30 to render the record-sheet B accessible for erasures. The aligning plate 52 includes a side-edge gage 58 and leading-edge gage members 59. The latter members, 59, intersect the face of the aligning plate 52 at obtuse angles and are rounded so as not to interfere with the feeding forward of a check A after it has been operatively positioned. The aligning plate 52 is slidable along the rod 30 to adjust the side gage 58 in position to correctly locate checks of any desired width. It is desirable to locate the ribbon-guides 26 beyond the side edges of the checks so that they will not interfere with the insertion of the checks in the machine, but it is also desirable to locate them as near to the side edges of the checks as practicable, so that the stretch of the auxiliary ribbon 21 between them will be short. Provision is made, accordingly, of a large number of holes 60 in the supporting brackets 29 for receiving the screws 36 by which the guides are attached to the brackets 29, so that the guides 26 may be adjusted in accordance with the width of the checks and the position of the aligning plate 52.

The record-sheet B is guided into the machine from the rear by adjustable side guides 61 on an extension 62 of the rear paper-shelf 63, which extension is secured to the platen-frame 19 by a rod 64 and brackets 65. The vertically-extending portions 37 of the brackets 29 may be used in co-operation with the side guides 61 at the rear of the machine to accurately locate the record-sheet. The aligning plate 52 at the front of the machine co-operates with these record-sheet guides to locate each check as it is inserted in the machine in predetermined relation to the record-sheet.

Variations may be resorted to within the scope of the invention, and portions of the improvements may be used without others.

Having thus described my invention, I claim:

1. In a typewriting machine, in combination, a platen around which a check-sheet and an underlying record-sheet may be disposed in typing position, a main vibrating ribbon for typing on said check-sheet, an auxiliary under-ribbon normally disposed at the printing line between said check-sheet and said record-sheet, means for shifting said auxiliary ribbon upwardly to an inoperative position, and ribbon-fenders for warding off said auxiliary ribbon, said fenders disposed above the printing line of said platen, and said fenders guiding the ribbon close to said platen whereby a new check-sheet may be inserted at the front of

said platen without danger of fouling said auxiliary ribbon.

2. In a typewriting machine, in combination, a carriage, a platen around which a 5 check-sheet and an underlying record-sheet may be disposed in typing position, a main vibrating ribbon for typing on said check-sheet, an auxiliary under-ribbon normally disposed at the printing line between said 10 check-sheet and said record-sheet, a frame on said carriage for supporting said auxiliary ribbon at the printing line, said frame being displaceable to move said auxiliary ribbon upwardly to an inoperative position, 15 and ribbon-fenders supported on said carriage between the ends of said platen for co-operation therewith to ward off said auxiliary ribbon, said fenders guiding said auxiliary ribbon circumferentially of and close against said platen so that it will not be fouled by a new check-sheet when the latter is being inserted at the front of the platen.

3. In a typewriting machine, in combination, a platen, typing elements, a main ribbon, vibratory at each type-impression, an auxiliary ribbon to cover the longitudinal printing line, means for shifting the auxiliary ribbon upwardly from effective to ineffective typing position, guides for the auxiliary ribbon to maintain it in uniform proximity to the platen at both shift positions, rolls on the ribbon-guides positioned above the ineffective position of said auxiliary ribbon to engage a work-sheet and hold it stationary, and means for pressing the ribbon-guides and rolls toward the platen, the rolls serving to space the ribbon-guides a working distance from the platen to promote a free movement of the auxiliary ribbon between its effective and ineffective positions.

4. A typewriting machine including a carriage and a platen, typing elements, a frame supported by the carriage, a ribbon carried by the frame to cover the longitudinal printing line of the platen, said frame being shiftable to render the ribbon operative or inoperative to the types, a rock-shaft supported by the carriage, ribbon-guides secured to the rock-shaft and co-operating with the platen to hold the ribbon parallel to and closely against the platen at both frame-shift positions, and means on said guides for spacing them a working distance from the platen.

5. In a typewriting machine, a revoluble platen, an inking ribbon extending lengthwise of the platen and movable from typing position upwardly to ineffective position, guides for said ribbon adjacent the platen, supports for the guides, a rock-shaft on which the guide-supports are pivotally mounted, means for yieldingly latching said 65 rock-shaft in effective position, springs tend-

ing to rotate the guide-supports relatively to said rock-shaft to press the guides toward the platen, and rolls on said guides and engageable with the platen to hold the guides spaced from the platen to guide the ribbon close to the platen, said guides being swingable away from said platen as a unit to release said ribbon for inserting a work-sheet thereunder.

6. In a typewriting machine, a platen-frame, a revoluble platen therein, ribbon mechanism comprising ribbon spools mounted for rotation about transverse horizontal axes adjacent the ends of the platen, guides mounted adjacent the platen to guide the ribbon, a rod above the platen and between the ribbon spools for supporting the guides, and yoke-supports for the rod extending around the ribbon spools and pivoted on the ends of the platen-frame, said yoke-supports serving also as handles for swinging the rod to raise the guides.

7. In a typewriting machine, a platen-frame, a revoluble platen therein, ribbon mechanism comprising ribbon spools mounted for rotation about transverse horizontal axes adjacent the opposite ends of the platen, guides mounted adjacent the platen to maintain the ribbon in proximity to the platen, a rod above the platen and between the ribbon spools for supporting the guides, and yoke-supports for the rod extending around the ribbon spools and having aligned bearings pivoted on the opposite ends of the platen-frame, the rod being held by the yoke-supports in alignment with their bearings so that rotation of the supports will swing the rod about a common axis.

8. In a typewriting machine, a platen-frame, a revoluble platen therein, guides adjacent the platen to serve as guides for a ribbon and for the margins of a work-sheet on the platen, paper-holding rolls carried by the guides to bear against said work-sheet, a rod above the platen for supporting the guides and holding the rolls, a ribbon-supply spool mounted between each end of the rod and the ends of the platen-frame, and yoke-supports for the rod to extend around the ribbon-spools and be supported at the ends of the platen-frame.

9. In a typewriting machine, a platen-frame, a revoluble platen therein, guides adjacent the platen to serve as guides for a ribbon and for the margins of a work-sheet on the platen, paper-holding rolls carried by the guides to bear against said work-sheet, a rod above the platen for supporting the guides and holding the rolls, a ribbon-supply spool mounted between each end of the rod and the ends of the platen-frame, yoke-supports for each end of the rod that are pivotally mounted upon the ends of the platen-frame, means yieldingly detaining the yokes against rotation to hold the guides

in proximity to the platen, and springs for each guide to hold the rolls against the work-sheet under pressure.

10. In a typewriting machine, a platen-frame, a revoluble platen therein, guides adjacent the platen to serve as guides for a ribbon and for the margins of a work-sheet on the platen, paper-holding rolls carried by the guides to bear against said work-sheet, a rod above the platen for supporting the guides and holding the rolls, a ribbon-supply spool mounted between each end of the rod and the ends of the platen-frame, yoke-supports for each end of the rod that are pivotally mounted upon the ends of the platen-frame, means yieldingly detaining the yokes against rotation to hold the guides in proximity to the platen, springs tending to swing the guides around the rod toward the platen, and means on the rod to limit the action of said springs as the rod is turned to lift the guides and rolls.

11. In a typewriting machine, a platen-frame, a revoluble platen therein, guides adjacent the platen to serve as guides for a ribbon and for the margins of a work-sheet on the platen, paper-holding rolls carried by the guides to bear against said work-sheet, a rod above the platen for supporting the guides and holding the rolls, a ribbon-spool mounted between each end of the rod and the ends of the platen-frame, yoke-supports for each end of the rod that are pivotally mounted on the ends of the platen-frame, means yieldingly locking the yokes in normal position to hold the guides in proximity to the platen, and springs connected to the rod and to said guides and arranged to press the rolls carried by the guides against the work-sheet.

12. In a typewriting machine, a platen, a shiftable ribbon disposed longitudinally of the platen, ribbon-guides to overlie the ribbon and the side margins of a work-sheet on the platen, a rod mounted in the carriage-ends to support the guides, springs for individually forcing the guides toward the platen, paper-holding means carried by the guides to bear against the side edges of the work-sheet and provide a free working space for the ribbon between the guides and the work-sheet, and means to raise the guides and ribbon to an inoperative position.

13. A typewriting machine including a carriage and a platen, typing elements, a main ribbon to cover the printing position at each type-impression, a frame supported to swing within the carriage, a pair of vertically-disposed ribbon-spools carried by the frame, an auxiliary ribbon carried by the spools, ribbon-guides carried by the frame to direct the ribbon lengthwise of the platen from spool to spool and cover and uncover the printing line by a swinging movement of the frame, a rod above the platen between the frame, a rod above the platen.

the two spools, yokes secured to each end of the rod to pass around the spool and take bearings within the carriage-ends, and means mounted upon the rod, adjacent the inner ends of each yoke, to bear against the face of the platen and overhang the front face of the auxiliary ribbon.

14. A typewriting machine including a carriage and a platen, typing elements, a main ribbon to cover the printing position at each type-impression, a frame supported to swing within the carriage, a pair of vertically-disposed ribbon-spools carried by the frame, an auxiliary ribbon carried by the spools, ribbon-guides carried by the frame to direct the ribbon lengthwise of the platen from spool to spool and cover and uncover the printing line by a swinging movement of the frame, a rod above the platen between the two spools, yokes secured to each end of the rod to pass around the spool and take bearings within the carriage-ends, and a roll-carrying guide mounted upon the rod adjacent each yoke, the roll thereof to bear against the face of the platen and the guide to overhang the auxiliary ribbon.

15. In a typewriting machine, a platen-frame, a revoluble platen therein, guides adjacent the platen to serve as guides for a ribbon and for the margins of a wide work-sheet on the platen, paper-holding rolls carried by the guides to bear against said work-sheet, laterally disposed supports for the guides, a rod above the platen on which the guide-supports are journaled, collars fastened on said rod on each side of said supports to hold them securely in position, springs connected to the rod and to said supports and arranged to press the rolls carried by the guides against the work-sheet, and means for adjusting the guides laterally along their supports to adapt them to work-sheets of different widths.

16. A typewriting machine including a carriage and a platen, typing elements, a main ribbon to cover the printing position at each type-impression, a frame supported to swing within the carriage, a pair of vertically-disposed ribbon-spools carried by the frame, braking means for each spool to prevent a free rotation thereof, an auxiliary ribbon carried by the spools, ribbon-guides carried by the frame to direct the ribbon lengthwise of the platen from spool to spool and cover and uncover the printing line by a swinging movement of the frame, a rod above the platen between the two spools, yokes secured to each end of the rod to pass around the spool and take bearings within the carriage-ends, and a roll-carrying guide mounted upon the rod adjacent each yoke, the guide overhanging the auxiliary ribbon and the roll bearing against the face of the platen to determine the degree of separation between the guide and the face of the platen.

17. In a typewriting machine, a revoluble platen, a shiftable ribbon, guides to hold the ribbon adjacent the platen at either shift position, a laterally disposed carrier for each ribbon-guide, a rod on which the carriers are rotatably mounted, a spring connected to each guide-carrier and to the rod for swinging the guides toward the platen, and cooperating means on the guides and their carriers for securing the guides to their carriers at laterally variable positions.
18. In a typewriting machine, in combination, a revoluble platen, work-feeding means, and an aligning plate formed with a leading-edge gage and a side-edge gage to locate the work in predetermined accurate relation to the platen, the leading-edge gage being constructed with a convex rounded surface whose axis is parallel with the axis of said platen to facilitate the feeding forward of the work over the leading-edge gage.
19. A typewriting machine including a carriage and a platen, typing elements, a main ribbon to cover the printing position at each type-impression, a frame supported to swing within the carriage, a pair of vertically-disposed ribbon-spools carried by the frame, an auxiliary ribbon carried by the spools, ribbon-guides carried by the frame to direct the ribbon lengthwise of the platen from spool to spool and cover and uncover the printing line by a swinging movement of the frame, a rod above the platen between the two spools, the position thereof being eccentric to the axis of the spools, yokes secured to each end of the rod to pass around the spool and take bearings within the carriage-ends, and ribbon-guiding means mounted upon the rod adjacent each yoke and formed with a curvature radial with the platen to overhang the auxiliary ribbon, to hold the ribbon a uniform distance from the platen during the shifting movement of the frame.
20. In a typewriting machine, in combination, a carriage, a revoluble platen, a front aligning plate having a side gage for locating work-sheets longitudinally of the platen, a rod pivotally supported by the carriage on which the aligning plate is rotatably mounted, means normally holding the aligning plate yieldingly against rotation relatively to the rod, work-sheet-holding means also mounted on the rod, means normally detaining the rod against rotation, and means for swinging the rod to raise the work-sheet-holding means and the aligning plate from the platen in unison.
21. In a typewriting machine, in combination, a revoluble platen, work holding and feeding means bearing against the platen, a front aligning plate above the platen and between the work-holding means, a rod carrying both the work-holding and the aligning plate and operable to swing the aligning plate and work-holding means to ineffective positions in unison, and interlocking means between the aligning plate and the rod whereby the aligning plate may be raised to an ineffective position independently of the work-holding means.
22. In a typewriting machine, a platen frame, a revoluble platen therein, guides for an auxiliary ribbon disposed adjacent the platen, a rod journaled above the platen by which the guides are carried, springs connecting said rod and guides to urge the latter toward the platen, an arm for each of said guides for swinging it upwardly about said rod against the action of its spring, and screw heads on the rod cooperating with said arms on the guides to limit the movement of the latter in the direction in which they are pressed by said springs, whereby all of said guides may be swung upwardly together to permit said ribbon to be moved away from said platen for inserting a work-sheet under said ribbon.

JESSE A. B. SMITH.
